UNITED STATES PATENT OFFICE.

DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY.

STEAM BOILER.

Application filed July 2, 1918. Serial No. 242,990.

To all whom it may concern:

Be it known that I, DAVID S. JACOBUS, a citizen of the United States, residing in Jersey City, in the county of Hudson and State of New Jersey, have invented certain new and useful Improvements in Steam Boilers, of which the following is a full, clear, and exact description, reference being had to the accompanying drawings, forming part of this specification, in which—

Figure 1 is a sectional side elevation of a horizontal water tube boiler constructed in accordance with my invention; Fig. 2 is a detail view of the headers of the high pressure stage of the economizer, shown in Fig. 1; Fig. 3 is a view similar to Fig. 1, showing another arrangement of the invention; Fig. 4 is a detail of Fig. 3, showing the arrangement of the superheating tubes; Fig. 5 is a view similar to Fig. 1, showing another form of the invention; Fig. 6 is another view similar to Fig. 1, showing another arrangement of the parts; and Fig. 7 is a front elevation partly in section of the form of Fig. 6.

My invention relates to that type of boiler wherein horizontally extending tubes, usually inclined to the horizontal, are connected into end headers which, in turn, are connected with one or more steam and water drums.

The object of the invention is to reduce the number of passes in the boiler, thereby reducing the draft drop and also discharge the gases at a lower point than is ordinary in such boilers, particularly in combination with an economizer system. It also relates to a spacing apart of the water tubes in groups, so as to provide for an outlet of the gases between the headers of the upper and lower groups, giving a good location for the superheater in the intermediate space or for a secondary combustion chamber, if the superheater is not employed.

The invention further relates to obtaining increased efficiency by flowing the gases along the lower tubes of the bank for substantially their whole length and then passing them upwardly through a contracting area flow space as they flow up between the tubes. It also relates to a combined boiler and furnace arrangement in which the gases produced through combustion flow through a progressively increasing area in the furnace in traveling from the fuel bed to the

boiler tubes, after which they contact with substantially the full length of the lowermost boiler tubes and later flow through progressively decreasing areas in passing over the boiler tubes.

In the drawings, referring to the forms of Figs. 1 and 2, 2 represents an upper bank of horizontally inclined tubes, and 3 a corresponding lower bank, shown as comprising three rows. The front and rear furnace walls are indicated by the reference numerals 40 and 41, respectively, the front wall being supported by a member 40^a, as indicated. The combustion chamber 4, below the lower set of tubes, extends substantially the entire length of the tubes and is of a hopper-shaped construction with the underfeed stoker 5 at the narrow part of the hopper, the front of the underfeed stoker 5 coming under the uptake headers 6. The rear wall of the combustion chamber is provided with a door 4' through which a tool may be inserted to remove the clinker which collects over the stoker dump plates.

The lower ends of the upper bank of water tubes enter a group of headers 7, while the lower ends of the lower tubes 3 enter headers 8, these headers 7 and 8 being connected by long spaced-apart nipples 9. A baffle 10, disposed at the rear of the boiler extends over the upper row of tubes 3 from the boxes 8 for a portion of their length, and from the inner end of this baffle a vertical baffle extends upwardly, being formed in part as the baffle 11 between the rows of tubes of the upper bank, and in part of superheater headers 12, 12^a, 12^b and 12^c and portions of baffling between them. In the form shown, the superheaters are provided with U-tubes 13, whose ends are connected to the boxes. It will be noted that the upwardly projecting part of this baffle extending through the bank is at an angle to the planes of the headers such that the upward flow space is gradually contracted as the gases rise through the tubes after flowing along substantially the entire length of the lowermost tubes.

The steam from the steam and water drum 14 passes through pipe 15 to the header box 12, thence through the U-tubes to the header box 12^a, whence it flows through nipples into box 12^b, and thence through the longer U-tubes to the upper box 12^c, where it is taken off. The gases rise from the furnace through

the lower group of tubes, pass up to the left of the baffles until they rise through the upper group of tubes, and then flow down through the upper group of tubes and out between the 5 nipples 9 to the offtake flue 16.

In the form shown, a two-stage economizer is provided, the high pressure stage being shown at A and the low pressure stage at B. The waste gases from the boiler flow 10 downwardly over the high pressure stage, and thence horizontally over the low pressure stage B. The high pressure stage preferably comprises oppositely placed horizontally extending headers 17, connected by 15 horizontally extending inclined tubes, the entire economizer arrangement being preferably in accordance with that shown in my Patent No. 1,281,016, issued October 8, 1918, for method of and apparatus for operating 20 steam boiler economizers.

The upper portions of the high pressure economizer headers are preferably connected at alternate ends by tubes 19 (Figure 2), which will allow the upward passage of 25 steam, air or gases, and avoid trapping. The low pressure stage is shown as consisting of three separate banks or groups of cast iron tubes, fitted into upper and lower cast iron horizontal boxes or headers. The spaces 30 between the banks provide for access to the tubes through ports shown at 20, and beneath each of the banks is a pit 21, for collecting steam condensed from the gases, or the water which may be used for washing the outside 35 of the tubes. A scraper system 22 is also provided for removing any soot that may be deposited on the low pressure banks. The feed water enters the last bank through pipe 23, and thence passes in parallel up through 40 the tubes of this bank to the upper headers, thence to the upper header of the next bank, down through said bank, and thence up through the third bank, nearest the high pressure stage, leaving the third bank through the pipe 24, leading to the tank 25. This tank is preferably provided with perforated plates, from which the water flows 45 to facilitate the disengagement and escape of air and gases from the water, such disengagement being assisted by the heating of the water in the low pressure stage, and if desired, by maintaining a partial vacuum in the tank by any suitable means, such as the dry vacuum pump 26; or the 50 gases may be permitted to escape through the relief valve 27. From the tank 25 the water is led by pipe 28 to feed pump 29, by which it is forced through pipe 30 to the lower part of the high pressure stage of the 55 economizer. The water enters the lowermost header of the economizer, and thence flows through the inclined tubes from side to side, through successive rows, and is delivered by pipe 31 into the steam and water 60 drum 14 of the boiler.

In Figures 3 and 4, I show a form similar to that of Figures 1 and 2, with certain changes as follows:

The underfeed stoker 5^a is shown under the downtake headers; the superheater tubes 70 13^a project inwardly from boxes 12^a placed in the opposite walls of the setting; a secondary superheater 13^x is provided above the upper bank of water tubes, these being shown as of the same type as the lower 75 superheater between the banks; and the waste gases in leaving the boiler through flue 16^a rise through the high pressure stage A^a of the economizer, and thence pass horizontally over the cast iron tubes of the low 80 pressure B^a of the economizer, which is set above the boiler. In this figure, parts similar to those of Figs. 1 and 2 are marked with similar numerals with the latter "a" applied thereto. 85

It will readily be appreciated that by employing two passes in the manner indicated in Fig. 3, a progressively decreasing flow area for the gases is secured. With the two-pass arrangement, the draft loss within 90 the boiler setting is considerably less than would be the case if three or more passes were employed, much of the decrease in draft loss resulting from eliminating the turns made by the gases in flowing over the 95 ends of the baffles, where the direction of the flow of the gases is changed through 180°. The economizer is particularly applicable in conjunction with a steam boiler of this type, as the temperature with the proper height 100 of boiler can be reduced to a point where the gases can be advantageously used with the economizer.

In Figure 5, I show a form similar to that of Figure 3, except that the underfeed 105 stoker 5^b is set under the uptake headers; the upper superheater 13^y is formed of U-tubes extending longitudinally with the boiler tubes, while the lower superheater 13^z is formed of S-shaped tubes; and the high 110 pressure stage A^b of the economizer is formed of vertically extending wrought iron or steel tubes connecting the upper and lower headers 17^b. In this figure, the parts similar to those of Figure 1 are marked with similar 115 numerals with the letter "b" applied.

In Figures 6 and 7, I show a form similar to that of Figure 5, except that underfeed stokers 5^c are provided under both the 120 downtake and uptake headers, giving double firing; the chamber between the two sets of tubes is not provided with a superheater and acts as a secondary combustion chamber, while a superheater 13^w is placed above the upper group of boiler tubes; and a horizontal baffling 18, extending alternately from opposite sides, is interposed in the high pressure stage of the economizer to give the gases back and forth passes therein, before they pass to the low pressure stage B^c. 125 130

In this form, the nipples 9^c are bent alternately forwardly and backwardly to provide a freer passage for the gases leaving the boiler. In this figure, parts similar to 5 those of Figure 1 are marked with similar numerals with the letter "c" applied.

The advantages of my invention will be apparent to those skilled in the art, and particularly in connection with economizer 10 practice. The two passes of the gases in the boiler reduce the draft drop provided on the ordinary boiler of the Babcock & Wilcox type; the gases are discharged at a more convenient height for using economizers; the spacing apart of the headers where 15 the gases pass through the connecting nipples provides an excellent space for a superheater, and if this is not used, for a secondary combustion chamber between the banks; 20 and the gases after passing through the lower group of tubes and being thoroughly mingled thereby, enter into secondary combustion in this chamber, this taking place whether the superheater is present or not. 25 By providing a free flow area between the lowermost tubes and the proper number of tubes in the lowermost bank, a lesser amount of the slag will be deposited on the superheater, as a greater number of the fused particles of slag will be cooled in flowing 30 through the spaces between the tubes to a degree that will cause them to be solidified before they come in contact with the superheater than would be the case with a smaller 35 flow area and an insufficient number of rows of tubes. To secure good results, there should be at least four rows of tubes in the lowermost bank having at least twenty-five per cent of the total heating surface of the entire boiler, and the lower bank should be 40 unobstructed by baffles so as to provide a free flow area of the gases between the tubes and into the superheater chamber. The particular arrangement therefore makes it possible 45 to keep the superheater free from slag and to maintain a more even degree of superheat than could be secured with a lesser flow area between the tubes of the lowermost bank and a lesser number of tubes in the 50 lowermost bank.

The advantages derived through the form of combustion chamber shown most clearly in Fig. 1, where the gases produced through combustion flow through progressively increasing areas in traveling through the furnace from the fuel bed to the boiler tubes and contact with substantially the full length of the lowermost tubes, are that the gases are made to impinge against the lowermost boiler tubes in a reasonably uniform way throughout their length, thus distributing the heat from end to end of the tubes and avoiding local intensification of action at certain points through a torch-like effect 55 of the flames. After distributing the gases

by means of the special form of furnace so that they contact with the entire length of the lowermost tubes, the gases are directed forwardly by the roof baffle and are made to flow into the lower part of the first pass, 70 after which they flow through progressively decreasing areas throughout the boiler, thus imparting a maximum amount of heat to the boiler with a minimum draft drop.

Building the front and rear walls of the setting so as to make them incline outward from a point adjacent the stoker ledge plates as shown in Fig. 1 is advantageous in maintaining the brickwork, as the weight of the wall in itself holds the walls in alignment 80 and prevents the walls from bulging inward. This element is important in connection with the high capacities at which 85 boilers and furnaces are now being operated.

The separately claimed features of my invention may be used in conjunction with the other features or not, as desired. Many changes may be made in the form and arrangement of the boiler and its parts, as 90 well as the economizer and its parts, if the latter is used, without departing from the spirit and scope of my invention.

What I claim and desire to secure by Letters Patent of the United States is:—

1. A boiler having horizontally inclined water tubes arranged in separated groups with space between the groups, end water compartments for the respective groups, the compartments at each end being connected together, an outlet for the gases leading from one end of the boiler between the compartments connecting the groups at this end, and baffling to direct the gases over the tubes to the outlet.

2. A boiler having water tubes arranged in spaced upper and lower groups, end compartments for the respective groups connected at one end of the boiler by nipples some of which are curved in planes substantially parallel to the water tubes, an outlet for the gases leading from the end of the boiler between the compartments of the upper and lower groups, and baffling to direct the gases over the tubes to the outlet.

3. A boiler having water tubes arranged in spaced groups, end compartments for the respective groups connected at one end of the boiler by bent tubes, an outlet for the gases around said bent tubes between the compartments connected by the bent tubes, and baffling to direct the gases over the tubes to the outlet.

4. A boiler having water tubes arranged in spaced groups, end compartments for the respective groups connected at one end of the boiler by tubes curved alternately forwardly and backwardly, an outlet for the gases leading from the end of the boiler between the compartments connected by the curved

tubes, and baffling to direct the gases over the tubes to the outlet.

5. In a boiler of the class described, inclined water tubes arranged in two groups, end compartments for the respective groups, the compartments at each end being connected together, baffling constructed and arranged to direct the gases across the lower group of tubes in a single pass and across the upper tubes in a double pass, and an outlet for the gases leading from an intermediate point of the height of the boiler between the compartments connecting the upper bank of tubes and the compartments connecting the lower bank of tubes.

6. In a boiler of the class described, inclined water tubes arranged in two groups, end compartments for the respective groups, the compartments at one end being connected together by nipples, baffling constructed and arranged to direct the gases across the lower group of tubes in a single pass and across the upper tubes in a double pass, and an outlet for the gases leading from an intermediate point of the height of the boiler through the nipples connecting the compartments of the upper bank of tubes and the lower bank of tubes.

7. A boiler having horizontally inclined tubes arranged in two separated banks, end water compartments to which the tubes are connected, said compartments being separated from each other at one end of the tubes, tubes connecting the said separated compartments, a gas outlet opening from the space between the separated compartments, a superheater between the banks, and baffling arranged to direct the gases over the tubes to the outlet.

40 8. In a boiler of the class described having tubes arranged in two separated banks, upper and lower water compartments to which the tubes of the respective banks are connected, nipples connecting the upper and lower compartments at one end, a baffle extending partially over the lower bank of tubes, a vertically extending baffle connected to the first main baffle and extending across the upper bank of tubes, a furnace beneath the lower bank of tubes, and an outlet leading from the nipples connecting the upper and lower compartments at one end, the gases having an up and down pass before they reach the outlet between the end compartments.

9. In a water-tube boiler of the class described having water tubes arranged in two separated banks, upper and lower compartments to which the tubes of the respective banks are connected, nipples connecting the upper and lower compartments at one end, a baffle extending partially over the lower bank of tubes and leading to a vertically extending baffle, a furnace beneath the lower bank of tubes, an outlet leading from the

nipples connecting the upper and lower compartments at one end, the gases having an up and down pass before they reach the outlet between the compartments, and a superheater between the banks of tubes and in the up-pass of the gases.

10. A water-tube boiler having horizontally inclined water tubes, end water compartments to which the tubes of the respective banks are connected, the tubes being arranged in separated banks, each bank being provided with compartments separated from the compartments of the other bank with a secondary combustion space between the banks, tubes connecting the separated compartments at one end, an outlet flue leading from the space between the separated compartments, and baffling to cause the gases to flow parallel to the tubes along a portion of the lowermost tubes and to confine the gases to a double pass up and down across the water tubes on their way to the outlet between the compartments.

11. A boiler of the class described having separated upper and lower banks of water tubes, end water compartments to which the tubes of the respective banks are connected, nipples curved alternately forwardly and backwardly connecting the compartments at one end, an outlet flue leading from the nipple connection, and baffling to cause the gases to flow parallel to the tubes along a portion of the lowermost tubes and to confine the gases to a double pass up and down across the water tubes on their way to the outlet.

12. A water tube boiler having front and rear vertically extending water compartments connected to two banks of horizontally inclined water tubes, the banks being spaced apart to provide a superheater chamber, said chamber having a height as great as that of a plurality of rows of water tubes of the upper bank, baffling for directing the products of combustion, said baffling having a longitudinal baffle extending from the lower ends of the tubes between intermediate rows of water tubes and above a plurality of rows thereof to expose the tubes below said baffle to the flame and gases for the major portion of their length and allowing a free unobstructed entrance of the gases to the superheater chamber at the high ends of the tubes, and an upwardly projecting baffle extending from the inner end of the horizontally extending baffle transversely of the water tubes above the superheater, and a superheater located in said superheater chamber and having tubes with return bends within the boiler setting, the tubes extending transversely of the boiler tubes and some of said superheater tubes being located within the upper portion of said chamber to prevent short-circuiting of the gases through that part of the chamber.

13. A water tube boiler having front and rear vertically extending water compartments connected by two banks of horizontally inclined water tubes, the banks being spaced apart to provide a superheater chamber, said chamber having a height as great as that of a plurality of rows of water tubes of the upper bank, baffling for directing the products of combustion, said baffling having a longitudinal baffle extending from the lower ends of the tubes between intermediate rows of water tubes and above a plurality of rows thereof to expose the tubes below said baffle to the flame and gases for the major portion of their length and allowing a free unobstructed entrance of the gases to the superheater chamber at the high ends of the tubes, and an upwardly projecting baffle extending from the inner end of the horizontally extending baffle transversely of the water tubes above the superheater and inclined to the vertical to restrict the upward flow of the gases above the horizontally extending baffle, and a superheater located in said superheater chamber and having tubes with return bends within the boiler setting, the tubes extending transversely of the boiler tubes and some of said superheater tubes being located within the upper portion of said chamber to prevent short-circuiting of the gases through that part of the chamber.

14. A water tube boiler having front and rear vertically extending water compartments connected by two banks of horizontally inclined water tubes, the banks being spaced apart to provide a superheater chamber, said chamber having a height as great as that of a plurality of rows of water tubes of the upper bank, a combustion chamber located below and extending substantially the entire length of the water tubes, under-feed forced-blast stoker mechanism in the lower part of said combustion chamber, baffling for directing the products of combustion, said baffling having a longitudinal baffle extending from the lower end of the tubes between intermediate rows of water tubes and above a plurality of rows thereof to expose the tubes below said baffle to the flame and gases for the major portion of their length and allowing a free unobstructed entrance of the gases to the superheater chamber at the high ends of the tubes, an upwardly projecting baffle extending from the inner end of the horizontally extending baffle transversely of the water tubes above the superheater, and a superheater located in said superheater chamber and having tubes with return bends within the boiler setting, the tubes extending transversely of the boiler tubes and some of said superheater tubes being located within the upper portion of said chamber to prevent short-circuiting of the gases through that part of the chamber.

15. A water tube boiler having front and rear vertically extending water compartments connected by two banks of horizontally inclined water tubes, the banks being spaced apart to provide a superheater chamber, said chamber having a height as great as that of a plurality of rows of water tubes of the upper bank, baffling for directing the products of combustion, said baffling having a longitudinal baffle extending from the lower ends of the tubes between intermediate rows of water tubes and above a plurality of rows thereof to expose the tubes below said baffle to the flame and gases for the major portion of their length and allowing a free unobstructed entrance of the gases to the superheater chamber at the high ends of the tubes, an upwardly projecting baffle extending from the inner end of the horizontally extending baffle transversely of the water tubes above the superheater and inclined to the vertical and to the tube axes to restrict the upward flow of the gases above the horizontally extending baffle, and a superheater located in said superheater chamber and having tubes with return bends within the boiler setting, the tubes extending transversely of the boiler tubes and some of said superheater tubes being located within the upper portion of said chamber to prevent short-circuiting of the gases through that part of the chamber.

16. A water tube boiler having front and rear water compartments connected by two banks of horizontally inclined water tubes, the banks being spaced apart to provide a superheater chamber, said chamber having a height as great as that of a plurality of rows of water tubes of the upper bank, baffling for directing the products of combustion, said baffling having a horizontal baffle extending from the lower ends of the tubes between intermediate rows of water tubes and above a plurality of rows thereof to expose them to the flame and gases for the major portion of their length and allowing a free unobstructed entrance of the gases to the superheater chamber at the high ends of the tubes, an upwardly projecting baffle extending from the inner end of the horizontally extending baffle transversely of the water tubes above the superheater chamber, and a superheater located in the superheater chamber and having transverse tubes with return bends extending from inlet and outlet headers on both sides of the boiler, some of the superheater tubes being within the upper portion of said chamber to prevent short-circuiting of the gases within the first up-pass of the gases through the boiler.

17. A water tube boiler having front and rear water compartments connected by two banks of horizontally inclined water tubes, the banks being spaced apart to provide a superheater chamber, said chamber having

a height as great as that of a plurality of rows of water tubes of the upper bank, baffling for directing the products of combustion, said baffling having a horizontal baffle extending from the lower ends of the tubes between intermediate rows of water tubes to expose them to the flame and gases for the major portion of their length and allowing a free unobstructed entrance of the 10 gases to the superheater chamber at the high ends of the tubes, an upwardly projecting baffle extending from the inner end of the horizontally extending baffle transversely of the water tubes above the superheater chamber and inclined to the vertical to restrict the upward flow of gases above the horizontally extending baffle, and a superheater located in the superheater chamber and having transverse tubes with return bends extending from inlet and outlet headers on both sides of the boiler.

18. In a water tube boiler of the class described, horizontally inclined water tubes arranged in two groups spaced apart to 25 form a chamber therebetween, the tubes of the lower group being exposed to the combustion chamber for substantially their entire length, and a baffle extending from the

lower parts of the lower group of tubes upwardly and forwardly and inclined to the 30 vertical across the chamber between the groups of tubes and having an extension within the upper group of water tubes.

19. In a water tube boiler of the class described, horizontally inclined water tubes 35 arranged in two groups spaced apart to form a chamber therebetween, the tubes of the lower group being exposed to the combustion chamber for substantially their entire length, and a baffle extending from the 40 lower parts of the lower group of tubes upwardly and forwardly and inclined to the vertical across the chamber between the groups of tubes and having an extension within the upper group of water tubes, said 45 extension within the upper group of water tubes forming an angle with that portion of the baffle extending across the chamber within the group of tubes.

In testimony whereof I have hereunto 50 signed my name in the presence of two subscribing witnesses.

DAVID S. JACOBUS.
